UNITED STATES PATENT OFFICE.

ARTHUR R. SANDT, OF MINNEAPOLIS, MINNESOTA, ASSIGNOR TO S. L. ALLEN & CO.,
INC., A CORPORATION OF PENNSYLVANIA.

DESIGN FOR A TRACTOR-WHEEL.

57,155.

Specification for Design.

Patented Feb. 22, 1921.

Application filed July 26, 1920. Serial No. 399,203. Term of patent 14 years.

To all whom it may concern:

Be it known that I, ARTHUR R. SANDT, a citizen of the United States, residing in Minneapolis, in the county of Hennepin and State of Minnesota, have invented a new, original, and ornamental Design for a Tractor-Wheel, of which the following is a specification, reference being had to the accompanying drawing, forming part thereof.

In the said drawing Figure 1 is a side and Fig. 2 is a front view of a tractor wheel showing my new design.

I claim:

The ornamental design for a tractor wheel, as shown.

ARTHUR R. SANDT.
